WATER SPRINKLER CONTROL HOUSING

Mario F. Fernandez, Minneapolis, Minn., assignor to The
Toro Company, Minneapolis, Minn.

Filed Sept. 29, 1972, Ser. No. 293,423

Term of patent 14 years

Int. Cl. D23—01

U.S. Cl. D23—38

FIG. 4

FIG. 1

FIG. 3

FIG. 6

FIG. 5

FIG. 2

FIG. 7

FIG. 1 is a perspective view of a water sprinkler control housing embodying my new design, showing the cover in a raised position;

FIG. 2 is a front view thereof, showing the cover in its closed position;

FIG. 3 is a top plan view of FIG. 2;

FIG. 4 is a rear view of FIG. 2;

FIG. 5 is a view taken from one side of FIG. 2;

FIG. 6 is a view taken from the side opposite that shown in FIG. 5; and

FIG. 7 is a bottom view thereof.

I claim:

The ornamental design for a water sprinkler control housing, as shown.
